INVENTOR
ALEXANDER VIRAG
BY
John A. Polecky
ATTORNEY

UNITED STATES PATENT OFFICE

ALEXANDER VIRAG, OF TOWNSEND, DELAWARE

SHIPPING BASKET

Application filed February 8, 1932. Serial No. 591,469.

This invention relates to new and useful improvements in a shipping wire basket.

The invention has for an object the construction of a shipping wire basket which is characterized by wires or straps extended across the bottom of the basket for the purpose of holding the bottom tightly, especially when the basket is heavily loaded.

As a still further object of this invention it is proposed to secure the wires or straps in place on the sides of the basket by the provision of staples of a construction to facilitate proper holding.

Furthermore, it is proposed to arrange a plurality of hoops encircling the basket and to place the wire or straps so as to be transverse to the hoops and thus provide a rigid and strong construction.

As another one of the objects of this invention it is proposed to mount staples on diametrically opposite sides of the basket, which staples are to have inclined portions, and to extend wires across the bottom of the basket and upon said staples in a manner so that normally the wires may be slack and when the basket is exceptionally loaded be moved to taut positions.

A still further object of this invention is the construction of an article of the class described which is of simple durable construction, dependable in use and efficient in action and which can be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a side elevational view of a basket constructed according to this invention.

Fig. 2 is a plan view of Fig. 1.

Fig. 3 is a perspective view of one type of staple used in the construction of the basket.

Fig. 4 is a perspective view of another type of staple.

Fig. 5 is a perspective view of a still further type of staple.

Fig. 6 is a side elevational view of a hamper constructed according to this invention.

Fig. 7 is a side elevational view of a bushel basket constructed according to the invention.

Fig. 8 is a side elevational view of a grape basket shown with the invention applied.

Fig. 9 is a fragmentary view similar to a portion of Fig. 1 but illustrating a modification of the invention.

Fig. 10 is a sectional view taken on the line 10-10 of Fig. 9.

The shipping basket according to this invention comprises a plurality of staves 10 and a bottom 11. A top hoop 12 is arranged around the top edges of the staves and the bottom hoop 13 around the bottom edges. The bottom hoop holds the lower ends of the staves against the periphery of the bottom disc 11. An intermediate hoop 14 between the hoops 12 and 13 serves to reinforce the staves intermediate of their ends. Wire straps 15 are secured at their ends 16 upon the top hoop by the use of one of the staples 17. This staple has merely a shank portion and a bent portion constituting the head. The strap 15 extends completely across the bottom disc of the basket. A staple 17 serves to attach the strap 15 upon the periphery of the disc 11.

At points, the hoop 12 is formed with tongues 18. Wires 19 are secured at one of their ends 20 upon the bottom hoop 13 and extends up around the hoops 18 and in this manner serve to rigidly hold the hoops against being separated. Each of the ends of the wire 19 are secured upon the bottom hoop 13 by the use of a nail or the like. In addition, a horizontal hoop 21 also encircles the staves 10 for reinforcing them in a manner similar to the strap 14. At certain of the intersections between the straps and between the wires there are staples 22 arranged. These staples have shank portions 23 for engaging into the staves and a horizontal portion bent upwards in the form of a hoop 24. The stem portions 23 straddle the straps or wires and the hoop portion 24 engage the

horizontal wires preferably from the bottom side upwards. This arrangement prevents the horizontal hoops from sliding downwards.

5 As shown on the drawing both straps 15, see Fig. 1, are extended across the bottom disc 11 to hold it firmly in place. Nails 25 are engaged through the bottom disc and the portions of the straps adjacent to firmly hold these parts together.

In Fig. 5, a modified form of staple has been illustrated which is provided with stem portions 23 and a hook 24^a having an inclined portion 26 with a stamped out finger 27 there along. This type of staple is used in the form of the invention illustrated in Figs. 9 and 10. A pair of diametrically opposite staples 24^a are mounted on the staves and a wire 28 has its ends slidably mounted upon these staples. The slidable mounting is accomplished by loops 29 upon the end of the wire engaging the inclined portion 26 of the staples. The wire 28 therefore has a certain amount of slack. Now then, when the basket is to be heavily loaded the loops 29 will be slid towards the high parts of the inclined portions 26 and held thereby the finger 27 which allows the loops to be slipped one way but restrain backsliding. In the new positions the wire 28 will be under greater tension and serve to better reinforce the basket. It is of great advantage not to originally have the wire under the greater tension in that the wood, that is the staves, will gradually give and the wire 28 would have lost its tension before the basket is used.

In Fig. 6 a hamper is disclosed which is constructed according to this invention. The staves are indicated by reference numeral 30, the hoops by numerals 31, 32, 33 and 34, and the wires or straps by numeral 35. Staples 22 are used at the junction of the wire or straps 35 with the hoops 32 and 33.

48 In Fig. 7 the invention has been shown applied to a bushel measure. Here the staves are indicated by reference numerals 36, the hoops by numerals 37 and 38 and the straps by numeral 39. At the junction staples 22
50 are used. It should be borne in mind that the straps 39 extend completely across the bottom of the bushel measure.

In Fig. 8 a grape basket has been shown which is composed of staves 40 reinforced by hoops 41, and 43. Straps 44 and wires 45 serve to reinforce the basket and staples 22 are used at the junction of certain of the straps, hoops and wires.

While I have shown and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim is new, and desire to secure by United States Letters Patent is:—

1. A shipping wire basket, comprising a plurality of staves and a bottom disc forming a basket, hoops along the tops, the bottoms and intermediate portions of the staves, wires and straps extended transversely between the loops and across the bottom of the disc, staples at certain intersections for holding the hoops against moving down, and staples serving to attach the wires or straps upon the staves, certain of said staples comprising a shank portion and a bent portion constituting its head.

2. A shipping wire basket, comprising a plurality of staves and a bottom disc forming a basket, hoops along the tops, the bottoms and intermediate portions of the staves, wires and straps extended transversely between the hoops and across the bottom of the disc, staples at certain intersections for holding the hoops against moving down, and staples serving to attach the wires or straps upon the staves, certain of said staples comprising a pair of shank portions connected by a hook portion.

3. A shipping wire basket, comprising a plurality of staves and a bottom disc forming a basket, hoops along the tops, the bottoms and intermediate portions of the staves, wires and straps extended transversely between the hoops and across the bottom of the disc, staples at certain intersections for holding the hoops against moving down, and staples serving to attach the wires or straps upon the staves, certain of said staples comprising a pair of shank portions connected by a hook portion, said shank portions straddling one of the wires or straps and the hook portion engaging from the bottom upon a crossing wire or strap. 95 100 105

4. A shipping wire basket, comprising a plurality of staves and a bottom disc forming a basket, hoops along the tops, the bottoms and intermediate portions of the staves, wires and straps extended transversely between the hoops and across the bottom of the disc, staples at certain intersections for holding the hoops against moving down, and staples serving to attach the wires or straps upon the staves, the top hoop having hooks bent therefrom and certain of said wires being engaged upon said hooks. 115 116

5. In a shipping wire basket, a plurality 120
of staves and a bottom element in the form
of a basket, hoops upon said staves, wires
and straps reinforcing said staves, staples on
diametrically opposite sides of the basket,
and having inclined mid-sections, fingers 125
stamped from said mid-sections, a wire ex-
tended across the bottom of the basket and
having its ends slidably engaged from the
inclined portions of the staples at the lower
points thereof so that the loops may be slid 130

to the high portions and held by the fingers to place the wire under tension.

6. In a shipping wire basket, a plurality of staves and a bottom element in the form of a basket, hoops upon said staves, wires and straps reinforcing said staves, staples on diametrically opposite sides of the basket, and having inclined mid-sections, fingers stamped from said mid-sections, a wire extended across the bottom of the basket and having its ends slidably engaged from the inclined portions of the staples at the lower points thereof so that the loops may be slid to the high portions and held by the fingers to place the wire under tension, said finger extending upwardly from the inclined mid-section.

In testimony whereof I have affixed my signature.
